DESIGN FOR AN EMBROIDERED TRIMMING OR THE LIKE

Hans Tobler, Teaneck Township, Bergen
County, N. J.

Application April 9, 1943, Serial No. 109,935

Term of patent 3½ years

To all whom it may concern:

Be it known that I, Hans Tobler, a citizen of the United States, residing in the township of Teaneck, county of Bergen, and State of New Jersey, have invented a new, original, and ornamental Design for an Embroidered Trimming or the Like, of which the following is a specification, reference being had to the accompanying drawing, forming part thereof.

The figure of the drawing is a plan view of an embroidered trimming or the like showing my new design.

I claim:

The ornamental design for an embroidered trimming or the like, as shown.

HANS TOBLER.
